LAUNDRY SORTING APPARATUS

James G. Mackechnie, Jr., Springfield, Mass.

Application April 2, 1948, Serial No. 18,512

2 Claims. (Cl. 214—11)

1

This invention relates to a selectively controlled sorting apparatus and has for an object a new and improved construction of the apparatus disclosed in my co-pending application Serial No. 757,768, filed June 28, 1947 now Patent No. 2,490,071, granted Dec. 6, 1949, for "Laundry Sorting Apparatus."

While the apparatus of my said prior application has many advantages in its suitability for the automatic sorting of a great variety of items, the tilting tray construction for depositing articles at pre-selected collecting stations was not found entirely satisfactory for all usages. In the handling of finished laundered articles, for example, the collapsible nature of ironed and pressed cloth requires special care. In the prior apparatus the articles are tipped from the tray and dropped at an angle. In many instances the ironed cloth becomes wrinkled and bunched, thus spoiling the appearance of finished laundry which has been prepared for packaging and delivery to customers.

An object of the new construction is, therefore, to provide an improved apparatus for handling collapsible articles of cloth such as ironed pieces of laundry and to avoid any wrinkling thereof. The new machine results in a simplified construction and a more efficient apparatus all things considered.

The many advantages of the present invention will be apparent from a consideration thereof in the following disclosure of a machine embodying the invention and illustrated by the accompanying drawings in which,

Fig. 1 is a side elevation of a section of the sorting apparatus embodying my invention;

Fig. 2 is a plan view of the section shown by Fig. 1;

Fig. 3 is a side view of an article holder pivoted to article releasing position;

Fig. 4 is a wiring diagram of the electric circuit controlling means for actuating the depositing mechanism;

Fig. 5 is a partial plan view of a modified form of article holder for the machine; and

Figs. 6 and 7 are side views showing the holder of Fig. 5 in article retaining and article releasing positions respectively.

In the drawings the conveyor means of the apparatus, as shown by Figs. 1 and 2, comprises a series of carriers 1 mounted in an endless track arrangement between a side table 2 and an inner shelf 3. Rollers 4 fixed to the facing edges of table 2 and shelf 3 extend under adjacent edges of carriers 1 and support the same for

travel in successive order over a series of receiving stations as bins 5.

The travel of the carriers is intermittent, providing for the step by step advance of carriers 1, each being brought to rest directly over each of the bins 5 in successive order. Reference is made to my aforesaid application for a means to advance the carriers. Any suitable mechanism may be used, the prior example mentioned having pusher means adapted for successively driving each carrier in the line of travel, each particular carrier being driven, pushing the others ahead of it.

Article holding and depositing means, shown by Figs. 1, 2 and 3, include a holder 6 in the form of a shallow basin or trough comprising two side portions 7 and 8 hinged along opposite outer edges thereof on pintles 9 and 10. Each end of pintles 9 and 10 is journaled in a bracket 11 on posts 12, the latter being mounted on the carrier 1 at the corners of an opening 13 of the carrier. The posts 12 are provided to maintain the holder in closed position above the carrier surface so as to avoid interference with any cross supports between table 2 and shelf 3. Preferably the side portions forming the holder are provided with end sections 14.

For the pivotal action of said side portions and fixed to one end of each of the pintles 9 and 10 is a crank 15 connected at its handle end to a throw arm 16 of a solenoid operated plunger 17. As will be described, solenoids 18 mounted on each carrier are energized to pivot the sides of the holder thereof for releasing an article at a pre-selected bin. When energized plungers 17 are extended to crank the pintles and sides as shown by Fig. 3. The plungers are normally held spring pressed to closed position.

Selective control mechanism for operation of a holder to deposit an article at a pre-selected bin station includes a series of pre-settable push button switch boxes 19 shown as mounted on table 2. Each switch box 19 is associated with a particular bin 5 for setting up appropriate electric circuits for the bin. A similar pre-settable push button switch box 20 is mounted on each of the carriers 1 and is for setting up appropriate circuits for the carrier. The mechanism for actuating the holders is mounted on the carriers as described. Each of the pre-settable switch boxes 19 is provided with a group of parallel electric circuits corresponding to a similar group in each of the switch boxes 20.

Positional switch means for connecting the corresponding circuits in a switch box 19 with

those in a box 20 comprise distributor contacts 21 mounted on the forward inner edge of a carrier 1 and finger contacts 22 mounted at each bin station on the shelf 2. As shown by Figs. 1 and 2, the contacts 21 and 22 for a particular carrier and bin station will be joined by the arrival of a carrier over the bin. In one complete circuit of carrier travel carrier contacts 21 will be joined in successive order to all the contacts 22 of the bins.

The wiring diagram of Fig. 4 illustrates the partial circuits of the pre-settable switch box mechanisms and the joining thereof by the positional switch means. The circuits on each carrier are at the left as in Fig. 4, the bin circuits at the right thereof. As shown, partial electric circuits are preset by push button keys 23. Assuming ten keys in each of the two rows, the top row may be assigned numbers from zero to nine and represent a unit value. The lower row may represent zero to nine of a decimal value. Thus circuits representing a numerical value from double zero to 99 may be set up by the keys.

Appropriate keys representing the number 29 are shown as depressed in Fig. 4 in connection with each of the switch boxes 19 and 20. The contacts 21 and 22 are joined as by the arrival of the carrier at a bin station. Solenoids 18 will thus be energized by the completion of the circuit to be described for actuating the crank arms and pivoting the side portions to article releasing position as in Fig. 3.

The circuits required for energizing the solenoids 18 may be traced first from a source of power 23 through line 24, the positional contacts, wire 25, decimal key 2 of box 20, wire 26, the positional contacts, wire 27, decimal key 2 of box 19, wire 28, a solenoid 29 controlling a switch 30 and line 31. Similarly the unit keys numbered 9 set up a similar circuit from line 24, wire 32, unit 9 of box 20, wire 33, unit 9 of box 19, wire 34, a solenoid 35 governing a switch 36, and wire 37 to line 31.

It will be noted that unless corresponding circuits are set up in each switch box either one or both of the solenoids 29 and 35 will not be energized to close switches 30 and 36. Only when both solenoids 29 and 35 are energized, as would occur in Fig. 4 on closing a line switch 41, is the circuit energized to actuate solenoids 18. This connection may be traced through line 24, the positional contacts, connector 38, the solenoids 18, connector 39, the positional contacts, wire 40, switches 30 and 36, and wire 37 to line 31.

Solenoid switches 30 and 36 are illustrated to indicate an available means for setting up additional rows of numbered push button keys to gain a greater selectivity of number combinations. By the addition of another solenoid switch similar to 30 or 36 with a third row of keys governing a group of pre-settable push button circuits, it would be necessary to have three numerically corresponding circuits for the three solenoid switches in order to energize solenoids 18 for depositing an article.

In the operation of the machine each bin circuit switch box is preset to correspond to a particular number, as a number which has been assigned to a particular customer's laundry. As each article of laundry is placed on a carrier, the carrier switch box 20 is preset to correspond to the customer's number. The carrier will advance step by step over each of the bins in successive order without energizing the solenoids 18 until such time as the carrier arrives at a bin which

has been assigned the particular customer's number. The article will be deposited in the bin. As the carrier moves past the bin contacts 22, solenoids 18 will be de-energized and the plungers 17 spring pressed as in Fig. 4 will be withdrawn to return the side portions of the holder to normal article retaining position.

It will be noted the pivotal swing of the side portions 7 and 8 as shown by Fig. 3 provide between the inner free edges thereof an opening space of the same dimension as the width of the bin. This dimension should be large enough flatwise to handle the largest size article which might be sorted in the particular apparatus. It will be readily understood that the bin might be designed with greater width and a correspondingly greater swinging arc be provided by the pivotal mechanism of the side portions.

Also shown by Fig. 3 are venting passages 50 in the sides of bin 5. It is the object of the centrally opened article depositing members to flap back so that a collapsible piece of laundry may fall flatwise in a straight vertical drop into a bin. If the cloth of an article is light enough the mere dropping of the same into a bin may create air resistance sufficient to cause disarrangement of the article in falling. With the venting arrangement for the bin, the chances of causing an uneven fall are lessened.

The preferred form of the holder as shown by Figs. 1 and 3 is seen to be shallow and trough-like in cross section. Having sloping concave sides it tends to cause a cloth article to slide more or less evenly into the bottom of the holder. Furthermore, as the sides are opened to article releasing position the edges of the articles tend to be guided to a position parallel with the sides of the bin. Thus, although an article may be placed by an operator angularly on the holder with respect to the sides thereof the releasing action of the holder with concave side portions will tend to correct the positioning as it falls into a bin. The most desirable result obtainable in depositing articles in the bin is to have the articles piled automatically in neat stacked form, a result which lessens the manual work in arranging the articles for packaging.

A modified form of article holder is shown by Figs. 5, 6 and 7 in which the side portions are horizontally disposed as side flaps 42 and 43. In this form the solenoids 44 are shown with a plunger action opposite to that of plungers 17 in order for the crank arms 45 to clear the carrier 1. The pivotal support for the side portions is provided by pins 46 journaled in brackets 47 on each corner of the carrier and brackets 48 at each corner of the flaps. It will be obvious this modification of the holder will not automatically assist in straightening the angular position of the article as it falls into the bin and will accordingly require care in properly placing the article initially on the holder in order to obtain a neat pile of articles in a bin.

Having described my invention, I claim:

1. In an automatic sorting apparatus having a series of traveling carriers, each driven in an endless path to convey an article to a preselected receiving station and each including a framed opening for dropping an article therethrough at said station, tray mechanism on each carrier for movement and release of articles to be sorted and comprising in combination two complementary tray side members movable to article holding and article releasing positions, said side members in holding position extending over the opening of a

carrier and having inner side edges in an adjacent facing edge to edge relation, the complementary outer side edges of said side members having pivotal connections to said carrier structure at opposite edges of the opening, releasing means on said carrier for said pivotal connections and normally holding said side members in article holding position, said side members in article releasing position hanging downwardly of the frame at said opposite edges of the opening.

2. In a laundry sorting machine having a series of traveling carriers, each driven in an endless path to convey articles to a preselected receiving station and each including a framed opening for passage of an article to be dropped at said station, tray mechanism on each carrier for movement and release of articles to be sorted and comprising in combination two complementary tray side members movable to article holding and article releasing positions, said side members in holding position extending over said framed opening of the carrier and having inner edges in an adjacent facing edge to edge relation, vertical bracket

supports on the carrier at opposite edges of said opening, pivotal members on the supports above the surface of the carrier, each of said side members being mounted at its outer edge on said pivotal members and formed with an arcuate surface to provide with its complementary side member a shallow basin for support of an article thereon when in holding position, solenoid operated crank means fixed to said pivotal members to actuate the latter and pivot said side members to article releasing position, said members in the latter position hanging downwardly through the carrier at opposite sides of said opening.
